UNITED STATES PATENT OFFICE.

FRANK L. GORMLEY, OF BROOKLINE, MASSACHUSETTS, ASSIGNOR TO A. O. NORTON, INC., OF BOSTON, MASSACHUSETTS, A CORPORATION OF MAINE.

LIFTING-JACK.

1,334,488.

Specification of Letters Patent. Patented Mar. 23, 1920.

Application filed March 24, 1919. Serial No. 284,842.

To all whom it may concern:

Be it known that I, FRANK L. GORMLEY, a citizen of the United States of America, and a resident of Brookline, in the county of Norfolk and Commonwealth of Massachusetts, have invented certain new and useful Improvements in Lifting-Jacks, of which the following is a specification.

This invention relates to lifting jacks and particularly to devices of this character designed for heavy work, the object of the present invention being the provision of means whereby the lowering of the movable member under great loads may be either automatically or manually controlled.

The invention is an improvement upon Letters Patent #1,287,966 granted to me Dec. 17, 1918.

The present invention consists in providing the jack with a revoluble shaft having secured thereon a brake disk adapted to coact with a manually operated brake member, said shaft also being surrounded by an automatic braking device operable under centrifugal action to impinge upon the cylindrical wall of a non-revoluble chamber within which said automatic governor operates.

The invention further consists of certain novel features of construction and arrangement of parts which will be more fully understood by reference to the description of the drawings and to the claims to be herein-after given.

For the purpose of illustrating the invention, one preferred form thereof is illustrated in the drawings, this form having been found to give satisfactory and reliable results, although it is to be understood that the various instrumentalities of which the invention consists can be variously arranged and organized and that the invention is not limited to the precise arrangement and organization of these instrumentalities as herein shown and described, except as required by the scope of the appended claims.

Of the drawings:

Figure 1 represents a horizontal section of a lifting jack embodying the features of the present invention, the cutting plane being on line 1, 1 on Fig. 2.

Fig. 2 represents a vertical section of the same on line 2, 2 on Fig. 1.

Fig. 3 represents a vertical section on line 3, 3 on Fig. 2, drawn to an enlarged scale.

Fig. 4 represents a vertical section on line 4, 4 on Fig. 3, and

Fig. 5 represents a horizontal section on line 5, 5 on Fig. 4.

Similar reference characters designate like parts throughout the several figures of the drawings.

In the drawings, 10 represents a suitable base supporting a stationary standard 11, over the outer periphery of which is fitted a movable sleeve 12, to the upper end of which is threaded a cap 13.

In the upper end of the standard 11 is mounted a nut 14 to which is threaded a lifting screw 15 having splined to its upper reduced end a bevel gear 16 with which meshes a bevel gear 17 formed upon or secured to a revoluble shaft or spindle 18, the outer end of which is provided with a suitable operating mechanism 19 of any well-known construction.

Between the upper face of the bevel gear 16 and the inner face of the cap 13 are two annular plates 20, 21, between which are interposed a plurality of anti-friction members 22.

The movable member 12 is provided on one side with a flanged projection 24 having a removable plate 25 secured thereto by bolts 26.

The plate 25 is provided with a bearing 27 for the spindle 18, and keyed to said spindle 18 between the inner end of said bearing 27 and the rear face of the bevel gear 17, is a worm gear 28 rotatable in either direction with the bevel gear 17.

The worm gear 28 meshes with a worm 29 formed upon or secured to a shaft 30 revolvably mounted in ears 31, 32 projecting inwardly from the plate 25.

On one end of the shaft 30 and adjacent to the ear 32, are two collars 33, 34 between which are interposed a plurality of anti-friction members 35, said collars 33, 34 being retained together by a ring 36 secured to the collar 33 and having an annular flange 37 extending over the outer face of the collar 34. The collars 33, 34 with the anti-friction members 35 form a thrust bearing for the shaft 30 on which the said thrust bearing is retained by a nut 38 threaded to the reduced end 39 of said shaft.

Loosely mounted on the opposite end of the shaft 30 is a spur gear 40 having a tapered annular flange 41 with which coacts

a disk 42 keyed to the shaft 30 and having a cone-shaped periphery adapted to contact with the tapered flange 41 of the gear 40.

The disk 42 is retained upon the reduced end 43 of the shaft 30 by means of the nut 44 threaded to said reduced end. When the movable member 12 is being raised, the worm gear will be rotated in the direction of the arrow *a* on Fig. 3 of the drawings 10 and the disk 42 will be separated from the flange 41 and no rotation will be imparted to the spur gear 40.

When a load is on the cap 13 tending to lower the member 12, the tendency would be 15 to rotate the worm gear 28 in a direction opposite to that indicated by the arrow *a* and the worm shaft 30 would be moved endwise, toward the right of Fig. 3, until the cone-shaped periphery of the disk 42 has 20 been brought into firm contact with the tapered flange 41 on the gear 40.

It is obvious that under these conditions any rotary movement imparted to the shaft 30 will be imparted to said gear 40 and 25 through it to the pinion 45 with which its teeth are constantly in mesh.

The pinion 45 is formed upon or secured to one end of a short shaft 46 revolubly mounted in the bearing 47 formed upon the 30 plate 25, said shaft 46 being provided at its end with a reduced portion 48 to which is keyed a brake disk 49.

The brake disk 49 is provided on one face with ears 50 to which are pivoted the links 35 51, said links having pivoted to their opposite ends at 52, other links 53, the opposite ends of which are pivoted to a collar 54 slideable upon the reduced end 55 of the shaft 46.

This reduced end 55 of the shaft 46 is 40 mounted in a bearing 56 formed in a lug 57 formed upon the cover plate 25.

The collar 54 is preferably keyed to the reduced end 55 of shaft 46 as indicated in the drawings.

45 The cover plate 25 is also provided with an inward projection 58 having a cylindrical chamber 59 therein:

To each pivot member 52 is pivoted a friction pad 60 adapted to coact with the 50 wall of the chamber 59 when the shaft 46 rotates at a predetermined speed thereby preventing the load from being lowered too rapidly.

A light helical spring 61 between the 55 brake disk 49 and collar 54 normally retains the collar in contact with the lug 57 with the friction pads 60 free from contact with the wall of the chamber 59.

Any excessive speed of the shaft 46 will 60 tend by centrifugal action to move the friction pads 60 outwardly into contact with the wall of said chamber 59 and by the frictional contact of these pads 60 with said wall, the speed of the shaft 46 will be retarded in an 65 obvious manner.

The cover plate 25 is provided with outwardly extending ears 62 to which is pivoted a brake member 63, one arm of which is curved to contact with the periphery of the brake disk 49 while the other arm 64 serves 70 as a means for manually separating said brake member 63 from the disk 49 when it is desired to lower the load.

The brake member 63 is normally held in contact with the periphery of the disk 49 75 by means of the spring 65 positioned in a socket 66 formed in the outwardly extending boss 67 of the cover plate 25.

The spring 65 acts upon a shoulder 68 formed on the outer end of the brake member 80 63 as indicated in Fig. 4 of the drawings.

As long as the brake member 63 is in contact with the disk 49, the worm 29 will be prevented from rotating and as a consequence, there can be no downward movement of the member 12.

The rapidity of the lowering of the member 12 will be automatically controlled by the 90 governor friction pads 60.

The pitch of the threads of the worm 29 is such that said worm may be rotated by the rotation of the worm gear 28.

In the operation of the jack, the worm gear 28 is revolved in the direction of the 95 arrow *a* when raising the load and at the initial movement of said gear 28, it will through the slight end movement imparted to the worm 29, disengage the members 41, 42 so that there will be no brake devices or 100 friction to retard the rotation of said gear.

When, under the load, the gear 28 begins to rotate in the opposite direction, the worm 29 will be moved in the opposite direction, the worm 29 will be moved endwise until the 105 members 41, 42 are engaged and then rotary movement will be imparted from the shaft 30 to the short shaft 46 through the gears 40, 45. At this time the brake member 63 will be disengaged from the brake disk 49, 110 said disengagement having been effected by the pressure of the hand of the operator upon the arm 64.

When, on account of an excessive load upon the cap 13, the member 12 moves 115 downwardly too rapidly, the greater speed of the shaft 46 will cause the friction pads 60 to impinge upon the wall of the chamber 59 and thereby automatically arrest the too rapid downward movement of the member 12.

When it is desired to arrest all further downward movement of the member 12, pressure is removed from the arm 64 and the spring 65 will force the brake member 63 125 into frictional contact with the periphery of the disk 49 and further rotation of shaft 46 will be prevented.

This makes a very simple mechanism for controlling the lowering of the jack and it is 130

believed that its operation and the many advantages of the invention will be readily understood without further description.

Having thus described my invention I claim:

1. In a lifting jack, the combination of a revoluble operating shaft; a worm gear keyed to said operating shaft; a worm meshing with and adapted to be rotated by said 10 worm gear and having end movement; a gear loosely mounted on the worm shaft; a member secured to said shaft adapted to be moved with said shaft into driving engagement with said gear during the lowering operation; a revoluble shaft parallel to said worm shaft; a pinion thereon meshing with said gear; a fixed cylindrical wall surrounding said parallel shaft; toggle arms revoluble with said parallel shaft; and friction 15 pads secured to said toggle arms and adapted by centrifugal action to be forced into engagement with said cylindrical wall.

2. In a lifting jack, the combination of a revoluble operating shaft; a worm gear 25 keyed to said operating shaft; a worm meshing with and adapted to be rotated by said worm gear and having end movement; a gear loosely mounted on the worm shaft; a member secured to said shaft adapted to be moved with said shaft into driving engagement with said gear during the lowering operation; a revoluble shaft parallel to said worm shaft; a pinion thereon meshing with 30 said gear; a fixed cylindrical wall surrounding said parallel shaft; toggle arms revoluble with said parallel shaft; a collar slideable on said shaft to which one end of said toggle arms are pivoted; and friction pads secured to said toggle arms and adapted by centrifugal action to be forced into engagement with said cylindrical wall.

ing said parallel shaft; toggle arms revoluble with said parallel shaft; a collar slideable on said shaft to which one end of said toggle arms are pivoted; and friction pads secured to said toggle arms and adapted by centrifugal action to be forced into engagement with said cylindrical wall.

3. In a lifting jack, the combination of a revoluble operating shaft; a worm gear keyed to said operating shaft; a worm meshing with and adapted to be rotated by said 45 worm gear and having end movement; a gear loosely mounted on the worm shaft; a member secured to said shaft adapted to be moved with said shaft into driving engagement with said gear during the lowering operation; a revoluble shaft parallel to said worm shaft; a pinion thereon meshing with 50 said gear; a fixed cylindrical wall surrounding said parallel shaft; toggle arms revoluble with said parallel shaft; a collar slideable on said shaft to which one end of said toggle arms are pivoted; a light spring surrounding said parallel shaft and tending to straighten said toggle arms; and friction pads secured to said toggle arms and adapted 55 by centrifugal action to be forced into engagement with said cylindrical wall.

Signed by me at 4 Post Office Square, Boston, Mass., this 21st day of March, 1919.

FRANK L. GORMLEY.
